UNITED STATES PATENT OFFICE.

ARTHUR KENDRICK, OF NEWTON, MASSACHUSETTS, ASSIGNOR TO INTERNATIONAL EQUIPMENT COMPANY, OF BOSTON, MASSACHUSETTS, A TRUST ASSOCIATION OF MASSACHUSETTS.

LAUNDRY-DRIER.

1,398,490.

Specification of Letters Patent. Patented Nov. 29, 1921.

Application filed May 19, 1920. Serial No. 382,555.

To all whom it may concern:

Be it known that I, ARTHUR KENDRICK, a citizen of the United States, and resident of Newton, in the county of Middlesex and 5 State of Massachusetts, have invented certain new and useful Improvements in Laundry-Driers, of which the following is a specification.

This invention relates to laundry driers of 10 the type in which the clothes to be dried are placed in a rotary reticulated or perforated drum inclosed in an air casing through which a current of hot air is circulated by suitable fans or blowers for the 15 purpose of absorbing the moisture from the articles to be dried.

Machines of this type comprise an outer casing for containing the rotary drum, the heating pipes and the air circulating means 20 and are partly subdivided by suitably arranged partitions into a drum compartment and a blower compartment in which are located the fan blowers which direct the currents of air over the heating coils through 25 a suitably located opening into the drum compartment so that hot air circulates through the rotary drum and may be returned through a suitable opening in the partition back to the blower compartment 30 provision usually being made to catch the lint carried by the air from the drum on a conveniently placed screen.

The present invention relates to the control of this air circulation so as to secure 35 any desired rapidity thereof within limits and also makes provision for preventing the clogging of the screen by so constructing and arranging the lint catching screen that it may be instantaneously dumped or dis- 40 charged of the lint without the necessity of having to open the casing for the purpose of removing the lint therefrom or removing the screen to clear the same.

One feature of the invention consists in 45 the arrangement of an air controlling shutter by which the hot moist air issuing from the drum compartment may be returned in whole or in part to the lower compartment for re-use, or may be partly or entirely di- 50 verted therefrom. Another feature of the invention consists in providing a construction and arrangement of screen that makes it possible to clear the screen of lint practi-

cally instantaneously after each run of articles to be dried and without the necessity of 55 opening the casing or stopping the machine.

These and other features of the invention will be particularly pointed out in the following specification and will be defined in the claims hereto annexed. 60

In the accompanying drawings I have illustrated one form embodying the principles of this invention in which:

Figure 1 is an end elevation showing the location of the heating coils, the various air 65 circulating partitions and the inclosing casing.

Fig. 2 is a sectional elevation showing the interior construction and arrangement of the air circulating passages and fan as well 70 as the adjustable shutter and dumping screen.

Fig. 3 is a detail view in front elevation showing the means for locking the shutter in its different positions of adjustment. 75

The inclosing casing *a* in which is mounted the drum shaft *b*' carrying the reticulated or perforated drum *b* is of suitable shape to properly inclose the rotary drum, the air circulating fans and the heating coils. At 80 its front upper portion it is provided with a door *a*² for affording access to the drum for the purpose of putting in and taking out the articles to be dried.

From a point below the bottom of the 85 drum *b* and quite close thereto is placed a curved baffle plate or partition *a*³ which follows the curvature of the drum to a point near the top of the rear side of the drum as shown in Fig. 1. To the front edge of this 90 baffle plate which extends the length of the casing is placed an inclined partition *a*⁵ whose lower end is attached to a longitudinal angle plate *a*⁶. On the inside of a door *a*⁵⁰ forming a portion of the front wall in this 95 instance, is placed a longitudinal ledge *a*⁷ which forms an abutment for the front edge of the screen *c*' the rear edge of said screen abutting against the angle bar *a*⁶ when the screen is in the normal operative position 100 as indicated in dotted lines in Fig. 1.

This screen is preferably curved and at its middle portion is secured to a rock shaft *c* which extends through the opposite end of the casing and is mounted in suitable 105 bearings formed by horizontal reinforcing

plates c^2 which have two properly positioned perforated lugs c^3 to receive the spring bolt c^4 in the operating lever c^5 by which the screen is reversed for dumping purposes. The screen is shown provided at its normally front edge with a reinforcing angle bar c^6 which in the reverse position serves to close the gap between the angle bar c^6 and the edge of the screen and which also serves to stiffen the frame work of the screen and keep it in alignment.

Near the bottom of the front wall of the casing a there is formed by means of the longitudinal plates a^8 a^9 forming partitions or false bottoms, an offtake passage leading to the offtake flue a^{12} which discharges into an offtake pipe a^{11} at the back of the machine. A screen d and an additional screen a^{10} serve to prevent the passage of lint into the offtake pipe. In the space between the baffle plate or partition a^3 a^5 a^9 and the wall c^{15} in front of the heating chamber are placed one or more fan blowers e through whose discharge outlets e' the air escapes through the partition a^{15} into the heating compartment containing the steam coils f , the intake of these fans being as usual on the side of the fan casing.

Near the bottom of the casing just above the partition a^9 is mounted a longitudinal rock shaft g extending through the opposite ends of the casing for a bearing support to which is secured a plate or shutter g of sufficient length to overlap the lower edge of the partition plate a^5 . The width of the shutter and the curvature of the screen c' are so correlated that when the screen is in operative position indicated in Fig. 1, the shutter is capable of swinging from one edge of the screen to the other against the adjacent angle plates a^8 c^6 while the edge of the shutter is close to the screen so as to prevent any substantial passage of air between the under side of the screen and the upper edge of the shutter.

To the outside of the end of the casing is secured the bracket g^3 having an arc shaped perforated member g^4 having perforations arranged in a series concentric to the rock shaft so as to engage the spring pressed locking pin g^5 forming the handle of a lever g^6 that is secured to the rock shaft g .

The operation of the device is as follows: When the clothes to be dried are placed in the drum and the door a^2 closed, the drum is rotated in the usual manner by means of the drum shaft b' , and the circulation of hot air established by the fans e over the heating coils f is maintained around the outside of the curved baffle plate or partition a^3 so that the hot dry air passes to the upper part of the casing down around the upper edge of said baffle plate and through the perforated drum and returns through the screen c' to the longitudinal compartment

below the screen in the front lower portion of the casing.

If the shutter g' be in the closed position indicated in Fig. 2, it is obvious that none of the air that has passed the drying drum 70 will return to the fan blowers but will pass through the screen d beneath the false bottom a^9 to the outlet flue a^{12} and the exhaust pipe a^{11} . If, however, the shutter g' be adjusted to its extreme forward position all 75 of the air that has circulated through the drum will be returned to the fan blowers and again circulated through the heating chamber back to the upper part of the drum. In Fig. 1 the shutter g' is shown in one of 80 its interior positions of adjustment in which a portion of the air returns to the blower while the other portion passes along to the discharge pipe. On one end of the casing covering the compartment containing the 85 fan blowers there is provided a screened opening h which may be wholly or partly closed by a sliding door h' so as to admit or exclude to any desired extent fresh air from outside.

After each drying run the operator dumps the lint catching screen c' by pulling out the locking pin c^4 forming the handle of the lever c^5 and swings it over until the locking pin is engaged with the forward perforated 90 lug c^3 by which movement the screen will assume the position as shown in Fig. 2 with its upper side underneath and with its front edge pressed against the underside of the angle bar a^6 . This is an operation which can 95 be performed practically instantaneously and the jar or shock caused by the edge of the screen striking against the angle bar a^6 causes the collected lint to drop to the bottom of the compartment, the shutter g' having previously been shifted to closed position 100 as shown in Fig. 2. Any loose particles of lint adhering to the screen when in reversed position will be instantly cleared off by the current of air passing through. It will be 110 noticed that with this arrangement the screen may be cleared after each run of clothes without loss of time and without having to open the casing to get access to the screen or to remove it for cleaning purposes. At the end of the day or of the week 115 the bottom of the trough or compartment lying below the screen and in front of the shutter g' may be cleaned when the machine is not in use by removing the lint therefrom through any suitable opening or door such as a' . The screens d and a^{10} serve to prevent the lint in this compartment from escaping into the room through the outlet pipe a^{11} .

On one end of the heating compartment is placed a removable slide door a^4 . The heating pipes are arranged in separate series of vertical coils f as indicated in Fig. 2 and the upper end of each such vertical coils is 130

connected to an inlet manifold f' and at their lower ends to an outlet manifold f^2 . In case of leakage of any steam coil the door a^4 may be slid open at the rear to expose the 5 coils for examination and the particular coil at fault may be uncoupled from its two manifolds and withdrawn from the casing without disturbing the other coils. This is a very useful and convenient feature of the 10 present invention.

I believe that I am the first to employ a dumping and self-clearing lint-catching screen that can be operated from the outside of the machine the advantages of which 15 have been explained.

What I claim is:

1. In a drying tumbler the combination of a casing, interior partition plates partly subdividing said casing into a drum compartment 20 and a blower compartment with openings for admitting the air from the blowers into the drum compartment and for admitting the air circulated through the drum back to the blower compartment, an adjustable shutter arranged to partly or wholly close the opening from the drum compartment into the blower compartment, a discharge conduit leading from said drum compartment to a discharge port whereby the discharge 25 of the air from the drum compartment into the blower compartment and the discharge passage may be controlled at will, substantially as described.

2. In a drying tumbler the combination of an outer casing, suitably arranged partition plates sub-dividing said casing into a blower compartment, and a drum compartment, a rotary drum mounted in the drum compartment said partition being constructed to provide 30 an opening to allow the passage of air from the drum compartment to the blower compartment, a discharge flue having communication with the drum compartment to conduct air outside the casing, and an adjustable shutter arranged to cut off the passage 35 of air into the drum compartment or into the discharge compartment at will, substantially as described.

3. In a drying tumbler the combination of an outer casing, partition plates arranged 40 therein to subdivide the casing into a drum compartment and a blower compartment, air circulating means mounted in the blower compartment, a rotary drum mounted in the drum compartment, an offtake flue leading 45 from the lower part of the drum compartment to the outside of the drum, an adjustable pivoted shutter pivotally mounted between the inlet opening of the blower compartment and the inlet opening of the offtake flue and adjustable to intermediate positions whereby the circulation of air through the blower compartment and through the offtake flue may be controlled at will, and 55 means for securing the shutter in its various

positions of adjustment to control the proportions of air entering the blower compartment and the offtake flue respectively, and means for heating the air discharged by the air circulating means before it passes 70 through the drum, substantially as described.

4. In a drying drum the combination of an outer casing and inner rotary drum air circulating means, air heating means, a partition partly subdividing the interior of the casing into a drum compartment and a blower compartment but leaving an opening for the passage of air from the drum compartment to the blower compartment, 75 an offtake flue provided with an inlet opening in communication with the drum compartment, a rock-shaft mounted in the lower part of the drum compartment, a shutter secured and guided thereby to move into 80 position to prevent the passage of air from the drum compartment into the blower compartment or the offtake flue according to its position of adjustment, a lever for actuating said rock-shaft and means for adjustably locking said lever in order to retain the shutter in different positions of adjustment, substantially as described.

5. In a drying drum the combination of a casing, a rotary drum mounted therein, air circulating means mounted therein, partition plates arranged to partly subdivide the casing into a drum compartment and a blower compartment with an opening left for the passage of air from the drum compartment to the blower compartment, a discharge opening for the passage of air from the drum compartment to the outside of the casing, an adjustable shutter for controlling the proportion of air passing through 100 to the blower compartment or to the outside of the casing, an inlet opening for admitting external air to the blower compartment, and means for controlling the size of said inlet opening, substantially as described.

6. In a drying tumbler the combination of a casing, a rotary drum mounted therein, air circulating means mounted therein, partition plates arranged to partly subdivide the casing into a drum compartment 115 and a blower compartment with a communicating opening to allow the air from the drum compartment to enter the blower compartment, a screen arranged in the drum compartment to prevent the lint from passing into the blower compartment said screen being movable into dumping position to discharge lint therefrom, substantially as described.

7. In a drying tumbler the combination of a casing partly subdivided into a drum compartment and a blower compartment with a communicating opening to allow the passage of air from the former to the latter, a discharge opening for said drum com- 125 130

- partment leading outside of the casing, adjustable means for controlling the flow of air into the blower compartment or the discharge passage respectively, and adjustable means for regulating the admission of external air into the casing to take the place of the air discharged therefrom, substantially as described.
8. In a drying tumbler the combination of a casing partly subdivided into a drum compartment and a blower compartment with a communicating opening for the passage of air from the former to the latter, a drum mounted in the former compartment, and a fan mounted in the latter compartment and a pivoted screen for retaining the lint from the air issuing from the drum, and means for shifting said screen from normal operative position to dumping position to discharge the lint therefrom, substantially as described.
9. In a drying drum the combination of a containing casing having interior air deflecting plates, a rotary perforated drying drum mounted therein, a heating coil and air circulating means for circulating the air over the heating coil through the drying drum, a screen arranged to intercept the lint carried by the air escaping from the drying drum, said screen being reversible to permit clearing the screen of accumulated lint at will, substantially as described.
10. In a drying tumbler the combination of an inclosing casing provided with internal deflecting plates and a perforated drying drum rotatably mounted in said casing, air heating coils, means for maintaining the circulation of air over the heating coils and through the drum and back again to the heating coils and drum, a shutter adjustably mounted in the casing to deflect a part or the whole of the air escaping from the drying drum to the outside of the casing according to its position of adjustment, and a pivoted screen mounted adjacent to said shutter and movable at will into position to dump the accumulated lint therefrom, substantially as described.
11. In a drying tumbler the combination of a casing partly subdivided into a drum compartment and a blower compartment with a communicating opening to allow the current of air issuing from the drum compartment to enter the blower compartment, a rotary drum and a fan mounted respectively in said compartments, a curved lint catching screen mounted in the lower portion of the drum compartment, an offtake flue for conducting the air from the drum to the outside of the casing, a pivotally mounted shutter shiftable along the under side of said curved screen and means positioning said shutter in various positions of adjustment to permit the air from the drum to pass either into the blower compartment or the offtake or partly into both in the desired proportions, substantially as described.
12. In a drying drum the combination of a casing inclosing a drum compartment and a blower compartment, a rotary drum mounted in the former and a fan in the latter compartment, openings being provided for the discharge of the moist air from the drum to the outside of the casing or to the blower compartment, a reversible screen pivotally supported in normal position to prevent lint from being carried into either opening, and a movable shutter beyond said screen shiftable to prevent the moist air passing through said screen from entering either of said openings or to pass partly into both openings, substantially as described.
- In witness whereof, I have subscribed the above specification.

ARTHUR KENDRICK.
